UNITED STATES PATENT OFFICE.

ARTHUR W. BRICE, OF ROCHESTER, NEW YORK, ASSIGNOR TO ROCHESTER SURGICAL APPLIANCE COMPANY, OF ROCHESTER, NEW YORK, A CORPORATION OF NEW YORK.

ELECTRIC-CURRENT REGULATOR.

No. 884,458.

Specification of Letters Patent. Patented April 14, 1908.

Application filed March 20, 1905. Serial No. 250,990.

To all whom it may concern:

Be it known that I, ARTHUR W. BRICE, of Rochester, in the county of Monroe and State of New York, have invented certain new and useful Improvements in Electric-Current Regulators; and I do hereby declare the following to be a full, clear, and exact description of the same, reference being had to the accompanying drawings, forming a part of this specification, and to the reference-numerals marked thereon.

My present invention relates to improvements in electric current regulators, and more especially to those which are particularly adapted to reducing the current from any convenient source to the proper degree in order to enable the use of lamps of very low capacity such as are used for medical purposes, and it is the purpose of my invention to provide a regulator of this kind which may be conveniently attached to an ordinary lamp socket, and which is capable of being manipulated in the most convenient manner in order to obtain the various regulations of current without the necessity of changing any of the electrical connections, and which is so constructed that the rheostat, or resistance coil may be easily formed and in operation will be reliable and durable.

To these and other ends the invention consists in certain improvements and combinations of parts all as will be hereinafter more fully described, the novel features being pointed out in the claims at the end of the specification.

In the drawings: Figure 1 is an elevation of an electric current regulator constructed in accordance with my invention; Fig. 2 is a top plan view of the same; Fig. 3 is a vertical sectional view on the line 3—3 of Fig. 2 showing the interior of the device; Fig. 4 is a perspective view of the impedance coil or rheostat removed from its casing; Figs. 5 and 6 are transverse sectional views taken on the lines 5—5 and 6—6, respectively, of Fig. 1; and Fig. 7 is a diagram illustrating the manner of connecting the circuits.

Similar reference numerals in the several figures indicate similar parts.

An electric current regulator embodying my improvements consists in the present instance generally of a casing which is built up of a cylindrical casing or shell 1, having the heads 2 and 3 at the top and bottom respectively which are preferably composed of

fiber, hard rubber or other suitable insulating material, the lower end of the casing being reduced in diameter and provided with an insulating sleeve or bushing 4, the latter being internally screw threaded to receive the corresponding threaded sleeve 5 which is adapted to serve as a socket for an ordinary incandescent lamp base, and connected to this sleeve 5 is a conductor 6 which leads to the central terminal 7 of the base 8, which is preferably of a similar construction to that of an ordinary incandescent lamp base, being provided with a screw threaded sleeve 9 which in the present instance is flanged and secured by the screws 10 to the end piece 2. Between the end pieces or heads 2 and 3 of the casing is mounted a drum or core 11 which is preferably formed hollow and provided at its ends with the reduced portions 12 and 13, and over these reduced portions are fitted the ends 14 of a swinging yoke member 15, the latter being provided with a brush or contact member 16 which embodies in the present instance a substantially straight rod having its ends bent to enter apertures 17 in the yoke in such a manner that it may swing freely between the drum and the yoke, a spring 18 being provided for exerting a force normally tending to hold the contact member in engagement with the drum.

If desired, the contact member 16 may be composed of a plurality of flexible plates or fingers to form a brush which will insure more perfect contact with the coil.

On the periphery of the drum 11 is wound a coil of resistance wire of German silver or other material which is suitable for the purposes of a rheostat, and it is preferable to form this coil of one continuous wire which is wound spirally from end to end of the drum to form a helix. Bare wire may be advantageously employed for this purpose, in which case a layer of insulating material is applied to the periphery of the drum, and suitable measures are taken to secure the insulation of each convolution of the wire relatively to the adjacent one. Extending diagonally across the periphery of the drum is an outwardly projecting rib or ridge 19 over which the wire is wound, and when the winding has been applied a portion of each convolution of the wire will be somewhat raised or elevated in such a manner that when the contact member 16 is moved circumferentially around the drum by a swinging motion of the

yoke 15 it will form a contact with each convolution successively, starting at one end of the drum where the first convolution is located and passing over uniformly to the last convolution of the coil.

In the insulating end 2 are fitted the binding posts 20 and 21 which are employed as the terminals through which the regulated current may be derived, the binding post 20 being connected by the conductor 22 to the last convolution at the lower end of the drum, and also to the conductor sleeve or socket 5, and the binding post 21 is connected by the conductor 23 to the sleeve 9, and through the screws 10^a to the drum 11, the latter being connected to the first convolution of the coil. To the swinging yoke member 15 is attached a pin 24 which is preferably insulated therefrom by the sleeve 25, a pinion 26 being revolvably fitted over this pin and provided with a milled operating head 27. This pinion 26 is arranged to coöperate with the toothed rack 28 which occupies a relatively fixed position on the casing, the operating head 27 being located at the exterior of the casing to enable it to be manipulated conveniently. This arrangement provides means whereby the swinging yoke 15 carrying the movable contact member 16 may be operated entirely from the outside of the casing, for it will be obvious that rotation of the head 27 will cause the pinion 26 to move along the toothed rack 28 of the casing, and consequently cause an oscillatory motion of the yoke 15 to which it is attached.

In order to employ a regulator of this character for the purpose of reducing the strength of a given current to a predetermined degree in order that extremely small lamps and other devices of comparatively low capacity may be employed on the circuit, it is simply necessary to insert the threaded member 9 into an ordinary incandescent lamp socket, the outer portion of this member serving as one terminal for the current and the central contact 7 serving as the other terminal, and within the lower socket 5 of the device is inserted a resistance of a known amount, an ordinary incandescent lamp 29 serving advantageously for this purpose. The conductors to which the lamp to be regulated is attached are then connected to the binding posts 20 and 21, respectively, at which time the contact member 16 should rest upon the last or lowermost convolution of the coil so that the latter will be completely short circuited, for it will be understood that the minimum amount of current will then be passing through the conducting wires of the lamp, and by manipulation of the operating head 27 the movable contact 16 will be moved successively into contact with the convolutions of the coil, and by referring to Fig. 7 of the drawing it will be seen that this will introduce in parallel with the small lamp

circuit, certain convolutions of the coil, which acts to vary the number of convolutions in the coil short circuited or shunted out above the contact member or brush, and this will cause a larger proportion of the current which is derived from the source, to flow through the circuit for the regulated current, and as the amount of resistance thus introduced is increased until it overbalances the resistance of the small lamp and its connections, the amount of current passing through the portion of the coil which is thus introduced will be diminished and the current passing through the lamp which is to be regulated, will be correspondingly increased, and by continuing the operation of the head 27, the contact 16 will be gradually moved over the various convolutions in the coil until it reaches a position where the resistance inserted in one side of the circuit will cause a current of the proper strength to pass through the lamp and produce a light of the desired brilliancy. This can be readily seen in the diagram, Fig. 7, for the current entering through the central contact 7 will pass along the conductor 6 to the central contact 6^a which bears upon the central terminal in the resistance lamp 29, and passing through the filament thereof and through the base 5, traverses the conductor 22, and as the latter is connected to the coil and to the binding post 20, the current will be divided a portion turning through the coil which is in series in the main circuit, and through the yoke 15 and the outer contact member 9 to the main conductors of the source of supply, the other circuit being through the binding post 20 to the conductor 30 and through the lamp, returning by the conductor 31 and the binding post 21, the latter being also connected to the terminal 9.

An arrangement of this kind renders it possible to use lamps or other devices of varying capacities without the necessity of changing the connections or substituting separate resistances, or other parts, as the coil is of a sufficient resistance to overbalance that of most lamps which are ordinarily used, and the regulation may be readily secured by properly manipulating the operating member 27 which is conveniently located on the exterior of the casing. Moreover, the manner in which the resistance wire is wound upon the drum to form the diagonal or spiral ridge to enable the movable contact member 16 to close the circuit successively with the various convolutions of the coil, is a particularly advantageous one, for it will be understood that the motion of the swinging yoke 15 is in a direction circumferentially of the periphery of the drum, and this insures a perfect and continuous contact of the member 16 with the coil during the various adjustments, as the motion of this contact member is in a direction substantially longitudi-

nally of the convolutions of the coil instead of transversely thereto, and this causes the contact member to gradually pass from one convolution to the adjacent one without interrupting the circuit through the coil.

Moreover, in regulating the current for the lamp, there is no liability of burning the lamp out by an excessive current which would probably result from an interruption of the circuit through the coil, as both ends of the resistance coil are permanently connected in the resistance circuit.

A device of this character embodying my improvements may be constructed at a reasonable cost, and in operation may be readily applied and manipulated, and owing to its comparatively simple construction, and the manner in which the contacts are made, it will be reliable when employed within the limits of its capacity, it being understood that the resistances and other parts may be varied in order to enable the device to be employed upon circuits of different voltages, and it will also be understood of course, that the resistance lamp 29 may be changed so that others of different resistance may be substituted in order to obtain different strengths of current from the source of supply without altering other parts of the device.

I claim as my invention:

1. In an electric current regulator, the combination with a drum or support having a coil of conducting material wound thereon, the latter being provided with a series of contact surfaces arranged on the periphery of the drum, of a pivoted member mounted to move circumferentially of the drum and a yieldingly-operated contact member on the pivoted member and arranged to coöperate with the contact surfaces of the coil.

2. In an electric current regulator, the combination with a drum or support having a coil of conducting material wound thereon, the latter being provided with a series of contact surfaces arranged on the periphery of the drum, of a pivoted member pivoted to the drum and arranged to move in a path circumferentially thereof, and a spring-operated contact member carried by the pivoted member and adapted to coöperate with the contacts of the coil.

3. In an electric current regulator, the combination with a drum or support, and a coil of resistance wire wound thereon having a series of contact surfaces, of a swinging member capable of moving in a direction circumferentially of the drum, and a pivoted, yieldingly operated contact member carried by the swinging member and arranged to coöperate with the contacts of the coil.

4. In an electric current regulator, the combination with a drum or support and a coil of resistance wire wound thereon having a series of contact surfaces arranged across

the periphery of the drum, of a swinging member capable of moving in a direction circumferentially of the drum, and a contact member pivoted on the swinging member and having a spring for causing it to coöperate with the contacts of the coil.

5. In an electric current regulator, the combination with a casing, and a drum or support inclosed therein and having a coil of resistance wire wound thereon, the latter being provided with a series of contacts, of a swinging arm capable of moving in a path circumferentially of the drum, a contact member carried thereby, and an operating member connected to the swinging member and having a pinion thereon coöoperating with a relatively fixed rack on the casing to enable the swinging member to be operated by manipulation of the operating member.

6. In an electric current regulator, a drum, a coil of resistance wire arranged thereon having a series of contact surfaces, a swinging member capable of moving in a path circumferentially of the drum, a contact carried thereby for coöperation with the contact surfaces, a fixed rack arranged about the drum, and a manually operable pinion rotatably connected to the swinging member and engaging the rack to move the contact on the swinging members.

7. A device for regulating currents comprising a casing, a drum within the casing having reduced ends, a coil of resistance wire arranged thereon having a series of contact surfaces, a swinging yoke member having its ends fitted over the reduced ends of the drum and carrying a contact for coöperation with the contact surfaces, and means operable from the exterior of the casing for swinging the yoke member to cause the contact to engage the contact surfaces.

8. A device for regulating currents comprising a casing, a drum within the casing having reduced ends, a coil of resistance wire arranged thereon having a series of contact surfaces, a swinging yoke member having its ends fitted over the reduced ends of the drum and carrying a contact for coöperation with the contact surfaces, and means operable from the exterior of the casing for swinging the yoke member to cause the contact to coöperate with the contact surfaces, said means comprising a pinion journaled on the yoke, a wheel connected to the pinion and arranged on the exterior of the casing, and a rack on the casing.

9. In an electric current regulator, a casing, a base carried therewith, a socket member carried also therewith, and having a contact electrically connected to one of the contacts of the base, a pair of binding posts one electrically connected with the other base contact and the other electrically connected to the other socket member contact, and a variable resistance within the casing having

electrical connection with the last mentioned binding post and socket member contact.

10. A device for regulating currents comprising a base, a socket member having one of its contacts electrically connected with a contact of the base, a pair of binding posts, one electrically connected with one of the contacts of the base and the other electrically connected with one of the contacts of the 10 socket member, and a variable resistance also connecting said contact and binding post.

11. A device for regulating currents comprising a casing, insulators at the ends of the casing, a base secured to one insulator, a 15 socket member secured to the other insulator, binding posts suitably carried by the device, and a variable resistance arranged within the casing and adapted to regulate the current passing to a device connected to the 20 binding posts.

12. A device for regulating currents comprising a drum, insulators connected to the

opposite ends of the drum, a base secured to one insulator, a socket member secured to the other insulator and having one of its contacts electrically connected to a base contact, a pair of binding posts carried by the device, one being electrically connected to a contact of the base and the other being electrically connected to a contact of the socket 30 member, a resistance wire wound about the drum and having a series of contacts, a swinging member carrying contact to coöperate with the contacts of the resistance, a casting surrounding the drum and the swinging member, and means for operating the swinging member from the outside of the casing to cause coöperation between the contact thereon with the series of contacts on the resistance.
